DESIGN.

G. F. ATKINSON.

PINCUSHION.

No. 8,583.

FIG. 1.

Patented Sept. 4, 1888.

FIG. 2.

FIG. 3.

FIG. 4.

ATTEST,

O. Hutton
John H. Redston

INVENTOR,

George F. Atkinson

UNITED STATES PATENT OFFICE.

GEORGE F. ATKINSON, OF SAN FRANCISCO, CALIFORNIA.

DESIGN FOR A PINCUSHION.

SPECIFICATION forming part of Design No. 18,583, dated September 4, 1888.

Application filed March 10, 1888. Serial No. 206,904. Term of patent 14 years.

To all whom it may concern:

Be it known that I, GEORGE F. ATKINSON, a citizen of the United States, residing in the city and county of San Francisco, in the State 5 of California, have invented and produced a new and original Design for Pincushions, of which the following is a specification, reference being had to the accompanying drawing, forming part thereof.

10 Figure 1 is a perspective view of one of my newly-designed pincushions in the form of a small pail or bucket. Fig. 2 is a perspective view of the same in the form of a tub. Fig. 3 is a transverse section showing the same as 15 Fig. 1, cut vertically through the center; and Fig. 4 is a transverse section showing the same as Fig. 2, cut vertically through the center.

The leading feature of my design consists in a circular body tapering toward the base, representing a pail or tub of the ordinary kind, 20 having a broad flat marginal configuration, provided with a pincushion filling the central field or space, as shown.

What I claim is—

The design for a pincushion herein shown 25 and described, the same consisting of a body portion therefor in the external form of a bucket or tub, A, with a recess or chamber having the cushion B, as set forth.

GEORGE F. ATKINSON.

Witnesses:

O. HILTON,
JOHN H. REDSTONE.
